UNITED STATES PATENT OFFICE.

HERMAN J. S. LEWIS, OF NEW YORK, N. Y., ASSIGNOR TO JOHN H. DALE,
OF NEW YORK, N. Y.

ELECTRIC SWITCH.

No. 843,901.

Specification of Letters Patent.

Patented Feb. 12, 1907.

Application filed July 2, 1906. Serial No. 324,338.

To all whom it may concern:

Be it known that I, HERMAN J. S. LEWIS, a citizen of the United States, residing at the city of New York, in the county of New York and State of New York, have invented certain new and useful Improvements in Electric Switches, of which the following is a full, clear, and exact description.

My invention relates to electric switches, and particularly those used for the purpose of incandescent lighting in which it is desired to operate different groups of lamps or different combinations of groups by a simple manipulation.

15. The principal object of the invention is to provide a pendent or hanging switch which has engaging buttons or devices thereon which may be manipulated to light any desired groups of lamps to which the switch is connected, either separately or in any combination.

20. A further object of the invention is to provide an extremely compact switch mechanism for obtaining the above effects and which is durable and cheap to manufacture and conformable to all the insurance regulations.

25. A still further object of the invention is to provide a switch in which the desired groups or combination of groups of lamps may be illuminated by separate buttons, but in which all the lamps may be extinguished by a single button.

With these and other objects in view the invention consists in the construction, combination, in the location, and in the arrangement of parts, as hereinafter set forth and shown, and finally particularly pointed out in the appended claims.

In the drawings, Figure 1 is a side view of 40 a multiple pendent switch embodying the principles of my invention. Fig. 2 is a side view, slightly enlarged, of the porcelain blocks or body upon which the metallic elements are fastened. Fig. 3 is a top view of 45 the same. Fig. 4 is a bottom view. Fig. 5 is a sectional view on the line V V of Fig. 3. Fig. 6 is a section on the line VI VI of Fig. 5 looking downward. Fig. 7 is a top view of the casing, showing the position of the circuit-wires. Fig. 8 is a bottom view of the casing, partly broken away. Fig. 9 is a section on the line IX IX of Fig. 3. Fig. 10 is a view from below of the parts in Fig. 9. Fig. 11 is a detail perspective view showing the 55 metallic plates which are engaged by the

switch elements. Fig. 12 is a detail sectional view showing one of the porcelain blocks employed. Fig. 13 is a perspective view showing the construction of the releasing-button.

For the purposes of private dwellings, hotels, and also for offices and all places where incandescent lamps are used it is desirable to have the lamps connected in groups, one or more of which may be illuminated at any time, as desired. For example, lamps may be placed on each floor or hallway of a building in groups of varying number, depending on the requisites of each location. Under these circumstances it would commonly be required to have all the lamps operable from 70 the lower hall.

In carrying out my invention I make use of an exceedingly compact pendent switch which may hang at a convenient point—for example, in the lower hall of a building—and which is capable of controlling the groups at various parts of the building—for example, on the various floors. When the need for the illumination has passed, all of the lamps may be simultaneously extinguished by the movement of a single release-button. This prevents any group being left inadvertently lighted.

In its broad aspects the invention includes a block of porcelain or insulating material 85 which is recessed symmetrically about a central axis and which has metallic clips or terminals fastened thereto, selected members of which may be bridged to establish a connection.

90. The device also has a releasing-button which is preferably disposed at the central axis of the appliance and which is capable of releasing all of the circuit-closing buttons thereof. The insulating block or blocks are 95 contained within a compact housing, through the upper end of which the circuit-wires are led away.

Referring now to the drawings, in which like parts are designated by the same reference-sign, 1 indicates a block of porcelain or insulating material, which is generally cylindrical in contour, but which is notched externally and recessed internally to receive certain metallic clips and parts. Externally the block has notches or cavities 2 deeply incut around its periphery. In this way there is provided between the various notches a series of ledges 3, which form partitions therebetween. The form of the various notches or 105

cavities 2 is different for the different notches around the circumference. In the structure shown there are four notches 2', which are exactly alike, while the remaining four notches 2'', alternating therewith, are of slightly-different form. The character of the notches 2' will be most clear from an inspection of Fig. 5, while that of the notches 2'' is illustrated in Fig. 9. Metallic clips are contained in these various notches and constitute terminals of separate circuit-wires.

Referring particularly to Fig. 5, it will be seen that the notches 2' have a face 4, which is parallel with the axis of the block. This face furnishes a guiding-shoulder on which the metallic clips rest. There is also provided in each notch a small cavity 5. 6 designate the clips, having ends 7, which are deflected inward, so as to enter the cavities 5. Each clip has a terminal screw 8 thereon, and the material of the block is cut away, as shown at 9, so as to provide a space for the terminal screw 8 to enter. The lower ends of the clips 6 extend downward, as shown at 10, below the plane of the lower edge of the block 1. The cavities 5 constitute the means for holding one end of the clip 6 in place. The other ends of these clips are held in place by a ring 11, of insulating material, which is of sufficient diameter to closely engage and surround the extremities 10 of said cavities, as shown in Fig. 5. 10' are enlargements on the clips, which engage the block 1 to prevent upward displacement. This ring-shaped block 11 has vertical passages 12 therethrough, which are arcuate in section and which are adapted to fall in alinement with the notches 2'' when the blocks are assembled in place. Through these passages 12 are passed the clips 13 and which enter the notches 2'' thereabove, as shown in Fig. 9. 14 indicate small metallic clips which have lateral extensions 15. 16 denote small machine-screws by which the clips 13 are secured to the clips 14. The form of the notches 2'' is such that the lateral extensions or lugs 15 engage the material of the block, as shown in Figs. 2 and 3, and serve to hold the clips 13 firmly up into place. By this construction it will be seen that when the clips are assembled within the notches and the ring 11 is positioned and the screws 16 driven into place that all the clips will be firmly held in proper relation. The clips 6 have the portions 10 exposed internally at four points within the ring 11, and the clips 13 will also have portions 17 exposed within or below the ring 11 at four points around its internal wall. In practice all of the clips 13 are extended, as shown at 17', so that such extensions lie directly below the parts 10 of the other clips. The clips 13 have terminal screws 18 thereon exactly similar to the screws 8 of the clips 6 previously described. The block 1 is also recessed at 19 to accommodate these terminal screws in a

manner similar to the recesses 9 above mentioned. It will be understood that the circuit connections are made to the terminal screws 8 and 18. Any circuit will be connected to adjacent clips having the relation 70 shown in Fig. 11, whereby the two would have the circuit difference of potential. It may be observed in passing that those clips which have the circuit difference of potential are separated at all points by a partition of 75 the porcelain or insulating block 1 or the ring 11. This is a desirable protection against fire and short circuits and is furthermore conformable to the insurance regulations.

Again referring to Fig. 11, it will be seen 80 that the clips 6 and 13 present faces which are in the same plane with one another and in vertical alinement. These faces are designated at 10 and 17', respectively, and I provide a switch element for each pair of clips 85 which coöperates with these faces and establishes an electric connection between them under certain circumstances. The form of these switch elements is best illustrated in Fig. 5, which also shows the relation of the effective parts of the metallic clips 6 and 13. 20 indicates a switch element formed of a metallic strip bent right-angularly at each end 21, so as to have generally U-shaped form. 22 indicate perforations in the extensions 21, 95 which may be slightly elongated in the direction of the extensions, if desired, as shown in Fig. 6. 23 is a spindle which passes through the openings 22 and is received in a cavity 24 in the block 1. Each spindle has a collar 25, 100 which engages a tension-spring 26 within the corresponding cavity and which serves the double purpose of guiding the inner end of the spindle and also impelling the same in an outward or downward direction. The lower 105 end of each rod or spindle 23 has an elongated button 27. These buttons are guided, as shown, in a cup-shaped part 28, which is preferably of porcelain or insulating material and which fits upon the ring 11, so as to inclose 110 the exposed metallic parts of the clips 13 and also furnish the guiding-holes 29, by which the buttons 27 are positioned and guided. I prefer in practice to have the disposition of the recesses 24 and the holes 29 such that the 115 spindles 23 have an outwardly-diverging relation with one another, as shown.

As already stated, the switch elements 20 are loosely supported on the spindles 23, which pass through the alined holes 22 of 120 said switch elements. The size of the holes 22 is such that the switch elements have a freedom of movement in a lateral direction at each end. Longitudinal movement on the spindles is, however, prevented by the 125 collars 25 and the buttons 27. 30 indicate springs, which are fixed to the switch elements 20 so as to present a rounded protuberance or portion 31 at the back of each of the switch elements and preferably at a point 130

between the planes of the two extensions 21. In practice I prefer to make use of leaf or blade springs 30, which are fastened at the upper end of the switch elements and depend 5 downward over the backs thereof, as shown.

Each of the springs 30 lies in such a relation that it may be engaged by a central longitudinal movable member 32, which I shall term the "releasing-button." In its preferred form this comprises a central rod or spindle having a button 33 at one end and guided at its opposite end in a hole 34. The button 33 may be made square with chamfered corners in practice, so that when 10 guided in a corresponding opening 35 in the part 28 the releasing-button will be prevented from rotary movement. It will, however, be free to have a longitudinal movement and is normally spring-impelled outward by the 15 spiral spring 36. This member or spindle 32 carries a block 37, of insulating material, which serves as a collar for the engagement of the spring 36 above mentioned and which also serves as an abutment for the springs 30 20 of the respective switch elements. The form of this releasing-button and its recessed block 37 is particularly illustrated in Fig. 13. It will be seen that the block 37 is square in outline and is recessed at four points 38 upon the 25 periphery, which respectively lie opposite the blade-springs 30. The bottoms of the recesses 38 are curved and have at their lower ends a ledge 39. In the normal relation of the parts all of the buttons 27 and the releasing-button 33 are outwardly spring-pressed and have the relation of the two right-hand buttons of Fig. 5. It will be seen that the protuberance 31 on the blade-spring 30 lies 30 below the ledge 39 of the block 37 on the releasing-button.

Before considering the operation I will refer to one or two features of the practical aspects of the invention. An important feature lies in the provision of a ledge 40, which 45 extends annularly around the internal surface of the ring 11, so as to lie between the clips 6 and 13 at the parts which are engaged by the switch elements. The initial part 41 of this ledge is substantially in the plane of 50 the extension 10 of the clip 6, so that the switch element may ride upon such surface 41. The lower part of the annular ledge 40 is, however, high enough to present a barrier to the movement of the switch elements and 55 also to the formation of any arc between the clips. The block 1, the ring 11, and the guiding member 28 are all assembled together in coaxial relation. In order to permanently hold the parts together, I provide screws 42, 60 which extend upward through the member 28 into aligned threaded holes 43 in two of the four clips 13. If desired, all of the clips 13 may have an extension 44 at their lower ends with a threaded hole 43; but in practice I 65 have found that it is sufficient to have only

two of the clips provided with extensions in this way in the relation shown best in dotted lines in Fig. 11.

The switch may be provided with any suitable casing 45, conveniently of spun metal, 70 of such shape and size as to snugly surround the contained parts. 46 indicates an insulating-bushing at the upper end of such casing, which incloses all of the circuit-wires 47, which lead to the terminal screws 8 and 18, 75 as above described. 48 is a cover-plate at the lower end of the casing, which is apertured for the various buttons 27 and 33 and which has a bayonet-joint or other fastening 80 49, by which it is positioned in place. When 82 the circuit connections are made and the plate 48 is assembled in this way, the device is complete and ready for use.

The operation is as follows: In the normal relation of the parts all of the buttons 27 and 85 33 are spring-impelled outward, as already stated, in which relation the protuberances 31 of the switch elements lie below the corresponding ledges 39 of the block 37. It will be observed that the switch element 20 is out 90 of contact with both of the clips 6 and 13 at this time. The upper extension of each switch element lies on the insulating-ledge 41, while the lower part of each switch element is out 95 of contact with the clip 13 by a fair interval. Thus I secure a two-point break of the circuit at each switch element, the break at 100 both points being as great as required by the insurance regulations and all requisites of prudence. I will now imagine that one of 105 the switch-buttons—for example, the button 27 on the left in Fig. 5—is depressed. This causes the protuberance 31 on the switch-blade 30 to ride over the ledge 39, after 110 which the spring tension impels the switch 115 element abruptly upward. Accordingly the circuit is made by an abrupt movement, and there is no likelihood of the switch element being left in a position where it makes an imperfect contact or where an arc might be possible. The switch element passes upward to the limit of its movement under the impulse 120 of the operating pressure and the blade-spring 30, which thereafter holds the switch element in such relation against return movement. Not only does the spring-blade 30 accomplish this function, but it also serves the further purpose of impelling the switch element inward at both ends toward the 125 clips 6 and 13. The switch element therefore makes electric contact at both clips and completes the electric circuit between them and between the corresponding terminals of this particular circuit. It is obvious that one button 27 may be depressed or two buttons or three or any number or group or combination, so that the lights of the connected circuits may be correspondingly illuminated in single groups or in any desired 130 combinations of groups. When, however,

the need for the illumination is past, it is merely necessary to depress the releasing-button 33. This impels inward the block 37 and moves all of the ledges 39 past the corresponding protuberances 31 of the blade-springs of each of the switch elements. If only one switch element is depressed, the releasing-button only moves past one such protuberance; but if all are depressed it moves past all of them. In any case the ledge 39 is pushed inward so far that it no longer serves as a support for the blades 30 against the outward pressure of the springs 24, and all of the buttons are accordingly impelled outward to open their circuits. Inasmuch as this motion is directly impelled by the springs 24, it is evident that it is accomplished with maximum suddenness, so that the circuit rupture at the switch elements is very abrupt. This is an exceedingly important feature of my invention, as will be obvious to those skilled in the art. When pressure is removed from the releasing-button 33, the latter returns outward under the influence of its impelling-spring 36, which should be somewhat stronger than the springs 24 of the other buttons.

What I claim is—

1. In an electric switch, a plurality of concentrically-disposed metallic clips, switch elements contacting therewith, and a single means for releasing all of said switch elements from such contact.

2. In an electric switch, a plurality of circuit-closing buttons, and a single button coaxially arranged thereto for releasing said circuit-closing buttons.

3. In an electric switch, a block of insulating material having a series of circumferential notches and terminal clips in said notches, said clips projecting below the lower edge of the block, and means for closing an electric circuit between any desired pairs of said clips.

4. In an electric switch, a block having a plurality of circumferential notches, clips in said notches each having a terminal screw, and means for connecting any desired number of adjacent clips whereby different electrical circuits are completed.

5. In an electric switch, an insulating-block having a plurality of metallic clips embedded therein, spring-impelled means for electrically connecting any desired pair of adjacent clips, and a spring-impelled button for releasing said means.

6. In an electric switch, a block of insulating material having notches around its circumference, clips contained in said notches each having a terminal screw, and movable switch elements having springs by which they are impelled to connect adjacent clips by an abrupt movement into circuit-closing relation.

7. In an electric switch, a block of insulat-

ing material having a plurality of terminal clips separated by insulating-partitions, switch elements for electrically connecting adjacent clips, and a releasing-button for releasing said elements into circuit-opening relation.

8. In an electric switch, an insulating-block having a plurality of circumferential notches, alternate notches having a recess therin, terminal clips having a bent-over portion contained in said recesses, additional clips lying intermediate said first-mentioned clips, and switch elements for connecting any desired number of such clips.

9. In an electric switch, a plurality of blocks of insulating material adapted to be fitted together in coaxial relation, terminal clips secured on one of said blocks and extending opposite the interior surface of another of said blocks, and a plurality of switch elements arranged to move over and connect any desired number of said terminal clips.

10. In an electric switch, a block of insulating material having notches, terminal clips in said notches and extending below the lower edge of said block, a second insulating block or ring of annular shape arranged to surround the lower ends of said terminal clips, switch elements inside said second block and means for moving each switch element into engagement with a pair of the terminal clips.

11. In an electric switch, a block of insulating material having notches, terminal clips in said notches and extending below the lower edge of said block, a ring of insulating material surrounding said lower ends of the clips, switch elements within said ring, and means for moving each switch element into engagement with a pair of the terminal clips.

12. In an electric switch, a porcelain block having circumferential notches, terminal clips in said notches and extending below the lower edge of said block, an insulating-ring surrounding said lower ends, and switch elements each having springs by which they are impelled into electrical contact with said terminal clips.

13. In an electric switch, a porcelain block having a plurality of notches, said notches being of two different characters, a set of terminal clips having bent-over extremities to fit into one group of said notches, and having lower ends which extend below the lower edge of said block, and another set of clips formed in two parts secured together and having lower ends with lateral arcuate extensions arranged to lie directly below the lower ends of said first-mentioned clips, and switch elements arranged to be moved into spring-impelled engagement with said clips.

14. In an electric switch, a plurality of metallic clips or contacts, a plurality of switch elements movable into spring-impelled contact therewith, and a releasing-button hav-

ing a ledge to trip said switch elements out of contact with the clips.

15. In an electric switch, a pair of clips connected to the wires of an electric circuit, a switch element having a spring by which it is impelled into contact with said clips, and a releasing-button having a ledge serving as an abutment for said spring and adapted to release said switch element when the button is depressed.

16. In an electric switch, a pair of clips connected to the wires of an electric circuit, a switch element spring-impelled into contact therewith, and a releasing-button having a ledge constituting an abutment for said spring and adapted to release the switch element when the button is depressed.

17. In an electric switch, a plurality of terminal clips arranged in a circle around a central axis, and a plurality of switch elements surrounded by said clips and movable to connect the different clips in separate pairs.

18. In an electric switch, a plurality of clips arranged in a circle around a central axis, and a plurality of switch elements surrounded by said clips and each longitudinally movable in the direction of said axis to connect the clips in separate pairs, and means for simultaneously moving all of the switch elements to disconnect all of the clips from one another.

19. In an electric switch, a pair of terminal clips connected to the wires of an electric circuit, a rod or spindle supported adjacent to said clips, a switch element of generally U-shaped form and loosely disposed on said rod or spindle, and a spring on said switch element whereby it is impelled toward the clips.

40 20. In an electric switch, a pair of terminal clips, a circuit-closing button having a spindle, a switch element loosely supported on said spindle and having a spring, and a releasing-button having an abutment for said spring whereby the switch element may be impelled into engagement with said clips.

21. In an electric switch, a plurality of

porcelain blocks having terminal clips and switch elements disposed therein, and having a releasing-button whereby the switch elements may be moved into circuit-opening relation, and a casing having an insulating-bushing surrounding said blocks and arranged to lead away the circuit-wires therefrom.

50 22. In an electric switch, a pair of terminal clips separated by an insulating wall or ledge, a U-shaped switch element arranged to extend over said ledge and connect the terminal clips when desired, and means for releasing said switch element whereby it is spring-impelled into circuit-opening relation.

60 23. In an electric switch, a pair of terminal clips, a switch element with a spring having a protuberance thereon, an abutment for said spring having a ledge to engage said protuberance, and means whereby said abutment may be displaced so as to release the switch element into circuit-opening relation.

65 24. In an electric switch, a plurality of concentrically-arranged circuit-closing buttons and a centrally-disposed releasing-button arranged to move all of said first-named buttons into circuit-opening relation when it is depressed.

70 25. In an electric switch, a porcelain block having a plurality of circumferentially-disposed terminal clips, a plurality of circuit-closing buttons arranged to connect adjacent pairs of said terminal clips, and a central releasing-button.

75 80 26. In an electric switch, a plurality of terminal clips having portions symmetrically disposed around a central axis, a plurality of switch elements also supported around said central axis, and spring-impelled into contact with said clips, and means for releasing said buttons whereby they are impelled into circuit-opening relation.

In witness whereof I subscribe my signature in the presence of two witnesses.

HERMAN J. S. LEWIS.
